UNITED STATES PATENT OFFICE

102,631

DESIGN FOR A DOCTOR'S CABINET OR THE LIKE

John Charles Fay, Chicago, Ill., assignor to Hamilton Manufacturing Company, Two Rivers, Wis., a corporation of Wisconsin

Application July 27, 1936, Serial No. 64,086

Term of patent 7 years

To all whom it may concern:

Be it known that I, John Charles Fay, a citizen of the United States, residing in Chicago, Cook County, Illinois, have invented a new, original, and ornamental Design for a Doctor's Cabinet or the like, of which the following is a specification, reference being had to the accompanying drawing, forming a part thereof.

The figure shows a perspective view of the cabinet embodying my design.

I claim:

The ornamental design for a doctor's cabinet or the like substantially as shown.

JOHN CHARLES FAY.
